CLAIM

The ornamental design for a rack server bezel, as shown and described.

DESCRIPTION

FIG. 1 is a front perspective view of a first rack server bezel having the claimed design.

FIG. 2 is a front view of the first rack server bezel of FIG. 1.

FIG. 3 is a rear view of the first rack server bezel of FIG. 1. FIG. 4 is a top view of the first rack server bezel of FIG. 1; and,

FIG. 5 is a bottom view of the first rack server bezel of FIG. 1.

(Continued)

The broken lines corresponding to a rack server and other features are environmental only and form no part of the claimed design.
